UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

DESIGN FOR A TRAFFIC SIGNAL.

Application filed May 7, 1926. Serial No. 17,605. Term of patent 14 years.

To all whom it may concern:

Be it known that I, CROMWELL A. B. HALVORSON, Jr., a citizen of the United States, residing at Lynn, in the county of Essex, State of Massachusetts, have invented a new, original, and ornamental Design for Traffic Signal, of which the following is a specification, reference being had to the accompanying drawing, forming a part thereof.

The figure is a perspective view of a traffic signal, showing my new design.

I claim:

The ornamental design for a traffic signal as shown.

In witness whereof, I have hereunto set my hand this 27th day of April, 1926.

CROMWELL A. B. HALVORSON, Jr.
